United States Patent Office

Des. 180,072
Patented Apr. 16, 1957

180,072

REFRIGERATED DISPLAY CASE

Edgar V. Dickson, Ladue, and Theodore E. Weber, Affton,
Mo., assignors to Hussmann Refrigerator Co., St. Louis,
Mo., a corporation of Delaware

Application December 5, 1955, Serial No. 39,174

Term of patent 14 years

(Cl. D80—11)

The figure is a perspective view of a refrigerated display case embodying our new design.

The rear of the refrigerated display case is substantially plain.

We claim:

The ornamental design for a refrigerated display case, substantially as shown and described.
